R. A. RIEK

DRIP PAN

Filed March 27, 1925

Patented June 16, 1925.

UNITED STATES PATENT OFFICE.

RUDOLPH A. RIEK, OF RHINELANDER, WISCONSIN.

DRIP PAN.

Application filed March 27, 1925. Serial No. 18,852.

To all whom it may concern:

Be it known that I, RUDOLPH A. RIEK, a citizen of the United States, residing at Rhinelander, in the county of Oneida and State of Wisconsin, have invented a new and useful Drip Pan, of which the following is a specification.

This invention relates to refrigerators and more especially to means whereby water of condensation accumulating upon the bottom surface of the ice tank and upon the outer surfaces of the walls of the tank can be collected without dripping into the provision compartment thereunder, the water thus collected, being carried off with the ice water.

One of the objects of the invention is to provide a drip pan which is out of the way when in use, does not detract from the appearance of the refrigerator in any way, and will act efficiently to collect all water of condensation formed upon any part of the ice tank.

Another object is to provide simple and efficient means for supporting the drip pan beneath the ice tank.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

40 In said drawings—

Figure 1 is a vertical section through the lower portion of the ice tank having the present improvements combined therewith, said section being taken from front to rear.

45 Fig. 2 is a section on line 2—2, Fig. 1.

Fig. 3 is a section on line 3—3, Fig. 2.

Referring to the figures by characters of reference 1 designates a portion of an ice tank, this tank being provided as ordinarily, 50 with a downwardly and rearwardly inclined bottom 2, the tank having its walls spaced from the lining L of the refrigerator and being provided, at its front, with an upwardly and forwardly inclined supporting apron 3 attached at its upper end to a portion of the front frame F of the refrigeration

tor. Thus it will be seen that the bottom 2 can project into a pan 4 which extends under the bottom and is also inclined downwardly and rearwardly, there being a drain pipe 5 projecting downwardly from the rear or lower portion of this pan.

An opening 6 is provided in the bottom 2 and is surrounded by a flange 7 which is curved upwardly, inwardly, and downwardly, this flange being provided at diametrically opposed points with openings 8. Another opening 9 is formed in the bottom of the pan 4 and is surrounded by a flange 10 adapted to project upwardly into the space 70 surrounded by the flange 7. This flange 10 is preferably curved as shown. Bendable tongues 11 are extended from the pan 4 and project through the openings 8, these tongues being bent down at their ends as shown at 12 so as to prevent downward withdrawal from the openings 8 and properly to support the pan from the bottom of the tank.

It will be apparent that when the pan is assembled with the tank as shown and described any water of condensation that may form upon the outer surface of the tank or upon the bottom thereof will drain downwardly into the pan because this pan extends outwardly beyond all sides of the bottom 2. Furthermore any water of condensation forming under the curved flange 7 will likewise drain into the pan. Obviously, therefore, when an ice rack of any preferred construction is placed over the opening 6 where it will rest upon the bottom of the ice tank, no moisture will drain downwardly into the provision compartment under the ice tank. Instead all of the moisture both 90 condensed and that resulting from the melting of the ice will be conducted to the pipe 5 and properly delivered from the refrigerator.

It will be seen that the pan can be applied readily simply by inserting the tongues 11 upwardly into the opening 8 and then bending down the upper ends of the tongues, as shown.

The bottom of the tank has an outlet opening 13 in the lower portion thereof through which ice water can drain into the drip pan.

What is claimed is:—

1. In a refrigerator the combination with an ice tank having an opening for the circulation of air through the bottom thereof, of a pan extending under the bottom of the tank,

- said pan and tank being spaced apart at all points, there being an opening in the pan for the circulation of air therethrough, and a flange surrounding said opening and projecting into the opening into the tank. 5 and being inclined downwardly toward the outlet, there being an opening in the pan for the downward flow of air leaving the 30 tank, a flange surrounding the opening and projecting into the opening in the bottom of the tank, and means for suspending the pan from the tank.
2. In a refrigerator the combination with an ice tank having an opening for the circulation of air through the bottom thereof, of means for collecting water of condensation 10 from the surfaces of the tank and ice water from the interior of the tank, said means including a pan extending under and surrounding the bottom of the tank, said pan and tank being spaced apart at all points, 15 there being an opening in the pan for the circulation of air therethrough, and a flange surrounding said opening and projecting into the opening in the tank.
3. In a refrigerator, the combination with an ice tank having an opening in the bottom thereof for the downward flow of air, and a drain opening, of means for collecting ice water from the drain opening and water of condensation from the surface of the tank, 20 said means including a pan extending under and surrounding the bottom of the tank, but spaced therefrom, said pan having an outlet 25
4. In a refrigerator, the combination with an ice tank having an opening in the bottom thereof for the downward flow of air, and a drain opening, of a drip pan extending under and surrounding the bottom of the ice tank but spaced therefrom, an opening 35 in the bottom of the pan for the downward flow of air leaving the tank, a flange surrounding said opening and projecting into the opening in the bottom of the tank, and bendable tongues extending upwardly from 40 the pan and through the bottom of the tank for supporting the pan from the tank. 45
- In testimony that I claim the foregoing as my own I have hereto affixed my signature in the presence of two witnesses.

RUDOLPH A. RIEK.
